COMBINED LAZY SUSAN AND CONTAINER

Martin Rosen, Flushing, N. Y.

Application July 30, 1953, Serial No. 26,186

Term of patent 3½ years

(Cl. D44—10)

To all whom it may concern:

Be it known that I, Martin Rosen, a citizen of the United States and a resident of the city of New York, county of Queens, and State of New York, have invented a new, original, and ornamental Design for a Combined Lazy Susan and Container, of which the following is a specification, reference being had to the accompanying drawing, forming a part hereof.

Fig. 1 is a top plan view of a combined Lazy Susan and container showing my new design; and

Fig. 2 is a side elevational view thereof.

I claim:

The ornamental design for a combined lazy susan and container, as shown.
